MACHINE FOR DIE-CUTTING PAPER

Elmer F. Noell, Cincinnati, Ohio, assignor to The
Printing Machinery Company, Cincinnati,
Ohio, a corporation of Ohio

Application March 25, 1948, Serial No. 16,983

9 Claims. (Cl. 164—21)

1

This invention relates to improvements in label cutting or trimming machines of the class utilized in die-cutting printed stacks of labels, booklets, calendar pads and the like.

Machines of this character employ a hollow or tubular cutting die cooperating with a power-operated cutting block or ram, the die being positioned above the ram and the work stacks being forced through the die during the upward stroke of the ram. The stacks, which previously have been blanked out to square or rectangular shape, are delivered by a feed plunger to the cutting block. Stationary guide plates are located around the cutting block so as to locate the stack in accurate registry with the die.

As the cutting block ascends toward the die, the stack is guided by these plates and is die-cut to required shape on being forced through the hollow die. The labels or work sheets have a printed face, which may or may not be enclosed by marginal lines, and the die is shaped to the desired contour. The work sheets are slightly over-sized so that on being forced through the die, the trimmed marginal edges of the stack follow the exterior surface of the die, eventually to fall into a discharge chute. The die-cut stacks pass through the die into a magazine rising from the top of the die.

A machine of this design is disclosed in my co-pending application, Serial No. 728,751, now Patent 2,483,735, granted October 4, 1949, to which attention is invited. The present improvements may be incorporated in this machine as well as in other paper-cutting machinery of this general nature.

In order to permit the stacked work sheets to be fed in upon the cutting block, it is usual to provide a slight amount of working clearance between the guide plates and the stack, otherwise it would be difficult to feed the stacks into cutting position. As applied to ordinary production, this slight amount of clearance has no particular significance, the work being of sufficient accuracy for most purposes. Greater accuracy, however, is required in many instances involving labels having intricate designs, in instances where the label has an irregular configuration, or must be trimmed more accurately with reference to the printing on its face.

Briefly, it is the concept of the present invention to provide spring-pressed guide elements associated with the guide plates in such manner that adequate clearance is provided at the lower portion, to facilitate feeding the stacks, but which take up this clearance as the upper portion of

2

the stack approaches the cutting edge of the die, thus aligning the face of the label with precision relative to the cutting edge of the die.

A primary object of the invention has been to provide guide means for paper cutting machines which align the stacked sheets with precision relative to the cutting edge of the die, so that work of ultimate accuracy may be produced.

A further object has been to provide an exceptionally simple automatic device for providing greater precision in the alignment of the stacks relative to the cutting edge of the die, operative upon the sheets of the stack just prior to the cutting operation, so that the guide plates may provide sufficient working clearance for receiving the stacks without having any adverse effect on the accuracy of the cutting operation.

Further objects and advantages of the invention will be more fully disclosed with reference to the drawings in which:

Figure 1 is a general vertical sectional view of a die-cutting machine embodying the present improved stack-engaging mechanism.

Figure 2 is a sectional view taken on line 2—2 of Figure 1, further illustrating the general construction of the machine.

Figure 3 is a sectional view taken on line 3—3 of Figure 1, illustrating the disposition of the stack-engaging devices with reference to the cutting block of the machine.

Figure 4 is an enlarged fragmentary side elevation detailing one of the forward guide blocks in which is incorporated the improved apparatus.

Figure 5 is an end elevation projected from Figure 5, further detailing the guide block structure.

Figure 6 is an enlarged fragmentary sectional view taken on line 6—6 of Figure 5, illustrating the structural details of the stack-guiding mechanism with reference to the guide block.

Figure 7 is an enlarged side elevation partially in section, illustrating the improved stack alignment mechanism as applied to the guide finger at the throat or feed side of the machine.

Figure 8 is an end elevation further illustrating the structure of the throat guide block.

Figure 9 is a diagrammatic sectional view illustrating the several parts of the apparatus at the start of the cutting stroke.

Figure 10 is a fragmentary side view, illustrating on an enlarged scale, the work-engaging end of the guide block in position shown in Figure 9.

Figure 11 is a diagrammatic view similar to Figure 9, illustrating the operation of the guide block as the work stack approaches the cutting edge of the die.

Figure 12 is an enlarged fragmentary view similar to Figure 10, further detailing the action of the apparatus during this operation.

Figure 13 is an enlarged fragmentary view similar to Figure 10, illustrating the action of the residue of the stack after completion of the cutting stroke and descent of the cutting block.

Described in general, the label-cutting machine, similar to that of my co-pending application, constitutes a base or pedestal which is disposed at an angle, as illustrated in Figure 1. Although the machine is disposed at an angle, for simplicity, the terms "vertical" and "horizontal" will be used in the specification and claims, these terms referring to the axis of the machine. Thus the work is maintained in stacked relationship by gravity against a back guide during feeding, and against guide plates during the cutting stroke, as hereinafter disclosed. As described in my aforesaid application, the work is placed by the operator upon a feed trough, and is engaged by a feed pusher and fed inwardly upon a cutting block or head which is arranged to reciprocate vertically in time with the movements of the feeder. When the stack is fed upon the cutting head, it is engaged by the guide plates and thus is maintained in alignment upon the head during the cutting stroke. A hollow cutting die is located immediately above the block so that the stack is thrust against the cutting edge of the die. This die is hollow and is shaped to the desired label outline. The blank labels are slightly oversized so that a marginal portion is trimmed off as the stack is forced through the die. That portion of the stack which extends beyond the confines of the die travels up the exterior of the die in the form of cuttings which are discharged from the machine, and the trimmed stacks are forced upwardly through the interior of the die, passing into a magazine rising above the upper edge of the die.

The present improvements are disclosed with reference to label-cutting machines of this general nature, but are not limited to a machine of identically the same design. As illustrated in Figures 1 and 2, the present machine constitutes a base or pedestal generally indicated at 15, having a drive motor and transmission unit generally indicated at 16. A spur gear of the transmission unit meshes with a gear 17, carried upon a shaft 18 journalled in the lower portion of the pedestal. This shaft has keyed to it a cam 20 for operating the ram plunger 21, and a cam 22 for operating the feed plunger.

A roller 23 is journalled upon the lower end of plunger 21 in contact with the periphery of cam 20. Upon the upper end of the plunger is mounted the cutting head or block 24. It will be apparent, therefore, that the ram plunger and cutting head will reciprocate vertically by rotation of cam 20. The ram is slidably mounted in the frame of the pedestal for reciprocation in the same manner as disclosed in my co-pending application. In the same manner, the four sides of the cutting block are slotted at 25 to receive the guide plates 26, 26a and 26b, and also guide finger 56 when the block 24 is elevated.

A hollow die 27 is mounted in alignment with and above the cutting block 24 by an adjustable mounting head, indicated generally at 28 (Figure 1). Mounting head 28 includes slide blocks 30 which are adjusted by means of cranks 31 having screw shafts 32 to permit convenient mounting and dismounting of the die. For this purpose, the upper edge of the die includes an undercut groove 33 arranged to key with a corresponding

groove formed at the inner edge of each slide 30. The mounting head 28 is carried by four columns or rods 34, rising from the work table 35 mounted at the top of the pedestal. Adjustment means, indicated generally at 36 (Figure 1), are provided to permit vertical adjustment of the mounting head assembly relative to the table. This adjustment permits the cutting edge of the die to be positioned accurately relative to the cutting block 24.

The uncut stacks of labels are fed into the machine by means of a feeder 37 which reciprocates in a horizontal plane lengthwise of the lateral extension 38 of table 35 (Figure 3). As previously noted, the feed plunger 37 reciprocates in timed relationship with the cutter block, being actuated by the cam 22. As shown in Figures 1 and 2, the feeder or pusher is actuated by a lever 40 having its lower end pivotally mounted in the pedestal as at 41, and having an angular foot 42, upon the end of which is pivotally mounted a roller 43. Roller 43 is in contact with the periphery of cam 22 to reciprocate the lever. The upper end of the lever carries a roller 45 in contact with a thrust member 46 carried by a slide 47. The opposite end of slide 47 is connected to the pusher 37 to cause reciprocation of the pusher. The slide is urged in feeding direction, in the present disclosure, by a weight 39, although a spring also may be used if desired. This causes the slide yieldably to be urged in feeding direction by the weight or spring and to be returned by positive cam operation.

In operation, the stacks are placed upon the table extension 38, resting against the back guide 43. As previously noted, the pedestal of the machine, similar to that of my co-pending application, is disposed at an angle (Figure 1) so that the stacks lean rearwardly against the back guide. This guide extends inwardly and in alignment with the back guide plate assembly generally indicated at 50. Therefore, the stacked relationship is not disturbed as the stack of blanks is fed by the pusher upon the cutting block which, at this stage of the cycle, is at its lower limit of travel, as shown in Figure 2.

The foregoing structure substantially duplicates that illustrated in my co-pending application, and for this reason, is described in a generalized manner. The present improvements are embodied in certain of the guide plates and in the guide finger, and are specifically described with reference to these parts.

As has previously been pointed out, the cutting block 24 has an individual slot 25 on each of three sides to accommodate the guide plates 26, 26a and finger 56, and a series of slots 25 at the rear to accommodate the series of guide plates 26b of the back guide assembly 50. During the upward movement of the head 24, the guides serve to maintain the blank stacks in alignment with the die, to position accurately the printed matter of the label relative to the cutting edge of the die.

Each guide plate is secured to an adjustment block 52 slidably mounted upon a rail 53, secured to the table 35. A crank 54 having a screw shaft 55 is journalled in a bearing block 49 also secured to the table. Each screw shaft 55 is in screw-threaded engagement with its block 52 so that the position of the adjustment block and the guide plate which it carries, may be regulated to compensate for stack sizes. The machine may be provided with a waste discharge chute 51 (Figure 1) following the structure disclosed in

my prior application. If desired, the chute may be made in sectional form, each plate being pivotally mounted as at 58, upon the slide block to permit collapse of the chute in the manner disclosed in that application. This chute serves to receive the cuttings which are trimmed from the marginal edge of the stacks as they are died out. These trimmings pass upwardly around the outside of the die, and the chute is disposed at an angle so as to discharge the cuttings by gravity as they fall upon it.

At the throat or work-receiving side of the cutter block, the machine includes a guide finger 56 which is maintained in an elevated position above the work table so that the stacks may pass beneath it (Figures 3 and 9). The mounting arrangement for the finger 56 is substantially the same as that for the guide plates with the exception that the adjustment block 52 and its crank 54 is located at one side to permit the stacks to pass beneath the finger as they are fed in. For this purpose the finger is joined to the adjustment block by a laterally extending arm 59. This structure likewise follows that disclosed in my copending application, the finger being provided with latch device which permits it to spring upwardly should the stack, by reason of size, jam beneath the finger. The latch mechanism is generally indicated at 60 (Figure 3), the arrangement including a rotatable shaft 61 which extends through the arm 59. The finger 56 is keyed to one end of the shaft and the latch is fixed on the opposite end so that pressure upon the finger will cause the detent or latch 60 to release, permitting the finger to snap upwardly under stress.

An automatic control switch 62, operated by an arm 63, likewise may be provided. Should the stack be over-size, this arm actuates the switch 62 to shut down the machine. The construction and operation of the finger 56 and switch 62 have been detailed in my co-pending application. However, it will be apparent that the present improvements may be applied to guide fingers having mounting arrangements other than that disclosed, without substantial change in structure or function.

In the die-cutting operation, the stack of labels, indicated at 65 in Figure 9, is fed in upon the cutting block 24 against the righthand guide plate 26a, the stack resting against the guide plates 26b of the assembly 50, by virtue of the slant of the table. The stack thus is held in alignment after the pusher 37 is retracted and the block begins its upward movement toward the die 27. The stroke of the ram plunger and block 24 is such that the block moves within predetermined proximity to the cutting edge of the die, then retracts, leaving a small pad of untrimmed blanks, indicated at 66, beneath the die. This is done to prevent the cutting block from contacting the cutting edge of the die, and to provide a means for supporting the trimmed labels which are retained in the die and magazine.

In order to support this stack of trimmed labels in the magazine, the guide plates conventionally have been equipped with spring-pressed detents indicated at 67. These detents, in the present instance, are mounted on the righthand guide plate 26a and the back guide plates 26b of assembly 50, as indicated in Figure 3. As the stack is pressed by the cutting block through the die, these detents are forced into a retracted position to permit the stack to pass, then spring outwardly to engage the bottom of the uncut pad 66, 75

as shown in Figure 9. It has been the practice in the past to provide each one of the guide plates and guide finger with a stack-supporting detent 67. The present improved structure embodies detents 67 only in guide plates 26a and 26b, and these cooperate with the new stack-engaging devices as hereinafter described.

The improved structure is designed primarily to provide more accurate registry of the face of the labels with respect to the cutting die. It will be apparent that normally a slight working clearance should be maintained between the guide members and stack, in order to permit the stack freely to pass between guide plates 26 and 26b in the feed stroke, and to pass the end of the finger 56 during the vertical cutting stroke. This clearance usually is in the neighborhood of $\frac{1}{16}$ of an inch. It will be observed that the stack, although resting by gravity against the guide plates 26b, will be disturbed upon passing the detents 67 just before the sheets of the stack reach the cutting edge of the die, to an extent permitted by the clearance between stack and guide plates. Normally, this degree of shift is not sufficient to affect the quality of the work. However, in the production of work requiring precision alignment, the stack must be aligned more positively and accurately relative to the die.

The improvements reside in the use of a co-operating spring loaded pressure plate and catch, indicated generally at 69. This structure is applied to the guide finger 56 and to the forward guide plate 26, see Figure 3. The structure and operation of this assembly is disclosed in Figures 4 to 8 inclusive.

As disclosed in Figure 6, illustrating the improved arrangement as applied to the guide plate 26, the inner edge of the plate includes a slot 70 milled in its upper corner. The spring loaded pressure plate or trigger 71 is slidably mounted at the upper end of slot 70 upon a pair of pins 72-72 which extend crosswise of the slot 73 formed in the inner end of the trigger bar 74. A hairpin-type spring 75, engaged upon a cross pin 76, has its opposite ends in compression between the inner end of bar 74 and the back edge of slot 70. The spring thus forces the trigger outwardly and the trigger tends to remain in the position illustrated with the rearward end of the slot engaged against the pin 72. A face or pressure plate 77 having an inwardly flared lower end 78, is mounted upon the outer end of the slide plate 74. This plate normally projects a predetermined distance beyond the edge 80 of the guide plate 26 and is adapted to be depressed into flush relationship with the edge 80 as the stack is fed through the die. As shown in Figure 4, the edge of the guide plate is provided with a notch 81 to receive the curved end 78 of face plate 77 when the plate is depressed.

Immediately beneath and symmetrical with face plate 77 is mounted a catch or detent 82. This catch is pivotally mounted upon a pivot pin 83 extending across the slot 70. A hairpin-type spring 84 engaged upon a crosspin 85 is disposed in compression between the rear edge of the catch and the rear edge of slot 70 to force the catch outwardly. A stop pin 86, likewise extending across slot 70, serves as a stop to limit outward movement of the catch. To permit a rearward movement of the catch, it is provided with an aperture 87 of sufficient size to provide ample clearance for the pin 86.

As viewed in Figure 5, the catch includes a relatively thin stack-engaging end 88, formed

preferably as an integral part of the catch as by milling. This portion of the catch extends beyond the surface of pressure plate 77 and is centered with respect to the plate as shown in Figure 5. For this purpose, the lower end of pressure plate 77 is slotted as at 90, clearance being provided to permit relative movements between the catch and the face plate.

This identical face plate and catch structure also is mounted upon the inner end of the guide finger 56, as shown in Figures 7 and 8, and therefore need not be described in detail. Upon reference to Figure 3, it will be observed that the stop finger 56 and forward guide plate 26, in which this mechanism is installed, are so related that the pressure plate 77 of guide plate 26 presses the stack toward the back guide plates 26b, and the pressure plate 77 of the finger 56 presses the stack toward the righthand guide plate 26a.

Upon being positioned upon the cutter block 24, the stack is maintained naturally on a slant toward the back guide plates 26b, and in contact with the righthand guide plate 26a. As shown in Figure 9, the pressure plate and catch assemblies 69 are located above the top of the stack so as not to interfere with feeding. As the block ascends (Figure 11) the upper sheets of the stack engage and depress the pressure plate and catch assemblies to maintain the stack under spring pressure in contact with guide plates 26a and 26b in the same relative position it initially occupied.

Referring to Figures 9 and 13, it is to be noted that the pad 66 of untrimmed labels is maintained under the die by means of the detents 67 and catches 82 after the upper portion of the stack has passed through the die.

As the cutter block ascends as shown in Figures 11 and 12, the catch 82 is depressed independently of the pressure plate 77 by the passing stack. Thus the stack is maintained by spring pressure against the guide plates 26a and 26b in accurate alignment with the die. Even if the alignment of the stack is disturbed in passing and depressing the detents 67, alignment is restored by the pressure plates 77 after the sheets pass above the detents. In other words, the sheets are pressed firmly into frictional engagement with the upper portions of guide plates 26a and 26b for realignment just before they reach the cutting edge of the die. Any portion of the stack which is out of line thereby is shifted accurately into alignment just prior to the cutting operation.

The cutting block is arranged to elevate so that its upper surface travels slightly above the top of the detent 67 and catch 82 as illustrated in Figure 13. The solid line 92, Figure 13, represents the bottom of the pad 66 at the upper limit of travel and the broken line represents the bottom of the pad resting upon the detents and catches and supporting the trimmed labels in the magazine after descent of the block. Thus the pad 66 is at all times spring pressed into positive alignment with the fixed guide plates 26a and 26b and is not disturbed when the catch 82 is depressed by the next stack due to the independent movements of the catch and pressure plate 77.

The structure and operation disclosed in Figures 9 to 13 are representative of the operation of the improved pressure plate and catch arrangement with respect to the guide finger 56 and guide plate 26a. It will be apparent, however, that the same conditions prevail with reference to the forward guide plate 26 and back guide plates 26b. In both

instances, the pressure plate 77 extends beyond the vertical plane of the guide plates so that as the edge of the stack engages the flared end 78, the face plate will be retracted under spring pressure and press the stack firmly against the opposite guide plate, thus taking up the clearance between the guide plates and stack.

It will be apparent, therefore, that with the guide plates properly adjusted relative to the die, the stack will accurately be positioned relative to the cutting edge of the die. There is no opportunity for the stack or for the individual labels in it to shift relative to the guide plates because of the action of the spring loaded pressure plates 77 as the sheets approach the die. It has been found by virtue of this arrangement that labels which must be cut precisely to a line or relative to the contour of a printed face can be cut with a greater degree of accuracy than has heretofore been possible. The improved structure, of course, may be utilized in cutting ordinary work as well as for work requiring exceptional accuracy of registration.

Having described my invention, I claim:

1. A machine for trimming stacks of blank sheets comprising; a hollow stationary die, a cutter block movable relative to said die, a feeder for positioning stacks of blanks upon said cutting block, guide plates for maintaining the sheets in stacked relationship during the cutting stroke, detents mounted in said guide plates and adapted to support an untrimmed portion of each stack successively, and a pressure plate arranged to force the stack into engagement against an opposite guide plate to align the stack relative to said die.

2. A machine for trimming stacks of blank sheets comprising; a hollow stationary die, a cutter block movable relative to said die, guide plates for maintaining the sheets in stacked relationship during the cutting stroke, detents mounted in said guide plates and adapted to support an untrimmed portion of each stack successively, and resiliently mounted pressure plates associated with said detents, said pressure plates arranged to force the stack into engagement against adjacent guide plates to align the stack relative to said die during the cutting stroke.

3. A stack cutting machine comprising; a stationary die, a movable cutter block, means for feeding stacks onto said cutter block, a guide finger and a plurality of guide plates for guiding said stacks relative to said die, said guide finger and an adjacent guide plate each including a resiliently mounted pressure plate located above the top of the stack in its feeding position, said guide finger and adjacent guide plate being spaced to provide clearance for feeding the stack onto the cutter block, and said pressure plates being adapted to force the stack into engagement with oppositely disposed adjacent guide plates to align the stack accurately with the cutting die during the cutting movement of the cutter block and stack.

4. A cutting machine for trimming stacks of work comprising; a stationary die, a movable cutter block, a feeder adapted to feed stacks of work to said cutter block, a guide finger disposed at the stack receiving side of said cutter block at an elevation to permit the stacks to pass therebeneath, a guide plate for said stack opposite said guide finger, said guide plate and finger spaced to provide clearance for the stack during the cutting stroke, said guide finger having a resiliently mounted pressure plate adapted to force the stack

into engagement with said opposite guide plate, whereby the stack is engaged against said guide plate to align the stack accurately relative to the die during the cutting with said pressure plate being disposed above the top of the stack in its feeding position to provide stack clearance between the guide finger and arranged to take up the clearance as the upper portion of the stack approaches the cutting edge of the die.

5. A cutting machine for trimming stacks of blanks comprising; a stationary die, a movable cutter block, a feeder adapted to feed stacks of work to said cutter block, a guide finger disposed at the stack receiving side of said cutter block at an elevation to permit the stacks to pass therebeneath, a guide plate for said stack opposite said guide finger, said guide plate and finger spaced to provide clearance for the stack during the cutting stroke, a pair of guide plates disposed at right angles to said guide finger and guide plate and spaced to provide clearance for the stack during the feeding stroke, said guide finger having a resiliently mounted pressure plate adapted to force the stack into engagement with said opposite guide plate and one of said adjacent guide plates provided with a resiliently mounted pressure plate to force the stack into engagement with its opposite guide plate, whereby the stack is engaged against adjoining guide plates to align the stack accurately relative to the die during the cutting stroke, said pressure plates being disposed above the top of the stack in its feeding position to provide clearance between the stack and guide plates during the feeding stroke and arranged to take up the clearance as the upper portion of the stack approaches the cutting edge of the die.

6. In a guide plate for a stack cutting machine, resilient means for engaging the stack with an opposite guide plate to align the stack, comprising; a pressure plate, resilient means for mounting said pressure plate relative to the guide plate, said means arranged to urge said pressure plate outwardly, a detent associated with said pressure plate, said detent having its edge extending beyond the plane of the pressure plate, means for causing the detent to be depressed upon engagement by the stack, said pressure plate and said detent being independently movable whereby said detent is adapted to spring outwardly in stack supporting position as the bottom of the stack passes the same and whereby the pressure plate is adapted to spring independently to stack alignment position.

7. In a guide plate for a stack cutting machine, resilient means for engaging the stack with an opposite guide plate to align the stack, comprising; a pressure plate, said guide plate having a slot adapted to receive said pressure plate, means for slidably mounting the pressure plate, a spring element for urging said pressure plate outwardly, a detent associated with said pressure plate, said

detent disposed substantially in centered relationship with said pressure plate and having its edge extending beyond the plane of the pressure plate, spring means for urging said detent outwardly and permitting the detent to be depressed upon engagement by the stack, said pressure plate and said detent being independently movable whereby said detent is adapted to spring outwardly in stack supporting position as the bottom of the stack passes the same and said pressure plate is adapted to spring independently to stack alignment position.

8. In a stack cutting machine having a guide finger and guide plates, resilient means for aligning the stack with said guide plates comprising; a pressure plate mounted on said guide finger and on one of said guide plates, a spring element for urging said pressure plate outwardly, a detent associated with each of said pressure plates, said detent disposed substantially in centered relationship with the pressure plate and having its edge extending beyond the plane of the pressure plate, said pressure plate and said detent being independently movable whereby said detent is adapted to spring outwardly in stack supporting position as the bottom of the stack passes the same and whereby the pressure plate is adapted to spring independently to stack alignment position.

9. In a guide plate and guide finger for a stack cutting machine, resilient means for establishing a frictional engagement of the stack with opposite guide plates comprising; a pressure plate respectively for said guide plate and guide finger, said plate having a mounting bar and said guide plate and guide finger respectively having a slot adapted to receive the same, means for slidably mounting said bar, a spring element for urging said pressure plate outwardly, a detent mounted in said slot and associated with said pressure plate, said detent disposed substantially in centered relationship with said pressure plate and having its edge extending beyond the plane of the pressure plate, spring means to cause the detent to be depressed upon engagement by the stack, said pressure plate and said detent being independently movable whereby said detent is adapted to spring outwardly in stack supporting position as the bottom of the stack passes the same and whereby the pressure plate is adapted to spring independently to stack aligning position.
